SUPPORT

Arthur T. Reynolds, Brooklyn, N. Y., and William F. Todé, Radburn-Fairlawn, N. J.

Application June 4, 1938, Serial No. 211,896

6 Claims. (Cl. 248—265)

This invention relates to an adjustable support for curtain rods and the like and is more particularly directed to a support for a plurality of curtains adapted for adjustment of the relation of the several curtains by moving one or more elements of the support with relation to another supporting element thereof.

The need for an adjustable bracket type support for curtain rods has long been recognized and numerous attempts have been made to provide such a device of sufficient flexibility to be adaptable under all conditions of use in connection with various types of curtains and drapes. Curtains made in standard lengths can be sold more cheaply than those which are specially tailored, but the dimensions of the interior trim around windows varies, and curtains of standard size are, therefore, generally unsuitable. Curtains and like decorations are frequently formed of certain fabrics which tend to stretch or shrink in use due to the nature of textile material used or the treatment used for cleaning, and thus may become so long that they no longer harmonize with the complete system of interior decorating for which they were originally designed. If the rod supports are of the standard type, elongation necessitates shortening of the curtains or relocation of the rod support. A copending application of Arthur T. Reynolds, Serial No. 186,039, filed January 21, 1938, a device is described for adjusting the hanging length of curtains, drapes, etc., by rolling on a rod. Although in most cases this is adequate to fit a single curtain to a window, where a difference of less than an inch can be tolerated, we find that even small differences between the bottoms of overlying drapes, e. g., side drapes and glass curtains, may be very unsightly. Such differences often cannot be cured even by relocation of brackets.

Moreover, relocation of brackets may in some cases be impracticable due to the manner of mounting on the wall, as where the interior wall of a room is finished with a minimum of wood-work. When possible, change in position of the bracket mounting inevitably leaves unsightly scars on woodwork which, even after repaired by filling with putty or the like, constitute ever present weakened areas which may become surface disfigurements if subjected to shock.

Further difficulties in this field arise from the practice on the part of transient tenants of moving drapes and curtains from one building to another. This is a source of annoyance to both tenant and landlord insofar as differences in window dimensions require the moving of brackets to

adapt them to preformed curtains. The landlord is thereby generally subjected to renovation costs to repair woodwork damage since the tenant, in anticipation of possible additional moves, is inclined to avoid curtain alteration whenever possible.

We are aware that various devices have been proposed for adjusting curtain rods and the like, but none is known to us which is satisfactory in respect to low cost, to ease of operation and installation, and to ruggedness and ability to perform its functions satisfactorily under all conditions.

Accordingly it is an object of our invention to provide a solution to these problems, especially in connection with multiple curtains, to permit the adjustable mounting of curtains and drapes relative to one another as well as to the window, as, for example, a valance and/or drapes together with a glass curtain.

Another object of the invention is to provide a simple and economical support for curtains and the like which is adapted to afford support fixed at any desired height within a limited range.

We have now devised a curtain rod support of the bracket type which avoids the difficulties of the prior art in a novel and effective manner. Our new device provides a bracket type support for curtains, drapes and the like of extreme flexibility in use and the invention contemplates the provision of a bracket adapted to support one or a plurality of rods carrying curtains or the like, at least one of which is instantly and easily adjustable to hold a curtain with its lower edge at any desired distance from the floor or other location.

The invention embraces a new concept in the manner of hanging a curtain, drape or the like, an important advantage of which is the avoidance of the possibility that the rod will be displaced by accident.

In a preferred embodiment of the invention we provide an element comprising a fixed means for removably securing a curtain rod support in any one of a plurality of positions and a curtain rod support adapted to be maintained in any one of said plurality of positions. Additional features of the invention are the configuration of the adjustable curtain rod support thereby providing a means of altering the effective length of the curtain without cutting or patching and the provision of one or more fixed rod supports which may be of similar or any other suitable configuration.

The nature of the invention in its preferred

form together with further objects and advantages thereof will be apparent from consideration of accompanying drawing wherein:

5 Fig. 1 represents one end of a valance and glass curtain assembly mounted on rods supported by our novel bracket;

Fig. 2 is a section along line 2—2 of Fig. 1 showing a different manner of affixing the glass curtain in the bracket;

10 Fig. 3 is a plan view of the fixed support member; and

Fig. 4 is a perspective showing of the adjustable support member.

As represented by the drawing, the preferred embodiment of our invention comprises fixed members 10 (of which only one is shown in the drawing) and adjustable supports 11. The member 10 is adapted to be permanently secured to the wall 19, which may be the casing of a window or doorway or any other vertical surface, by nails, screws or the like 12 advantageously fitted into keyhole slots 13, which permit the entire curtain assembly to be removed and replaced as a unit. The member 10 may conveniently be formed of two pieces of strip metal in the manner shown. The part 14, of member 10, carrying a supplemental rod supporting seat 15 is permanently fixed to part 16, e. g., by rivets 17, welding or the like, and may be provided with a hole 17' through which a wood strip may be screwed onto this part for custom draping. The part 16 is formed with a number of apertures 18 in a face parallel to and spaced from the wall 19. This two piece construction permits combining of several sizes of the parts 16 with a single standard sized part 14.

40 Adjustable support 11 is also formed of strip metal, preferably identical with that forming member 10, and designed to have at one end a tongue 20 adapted to enter one of the apertures 18 to secure support 11 in any desired position on the face of member 10. The other end of support 11 is bent to form a rod supporting seat 21 of novel shape as will be hereinafter more fully discussed.

45 The form of the tongue 20 and of the apertures 18, although not essential to any invention in its broader aspect, is important. The upper and lower surfaces of both the tongue and aperture are rounded and the lower surface of the tongue fits closely to the lower edge of the aperture while the upper surface is spaced from the top of the aperture only far enough to allow the tongue to move diagonally upward through the 50 aperture for removal. The result of this is that the support 11 cannot be accidentally removed from the member 10 by swinging the portion 21 or by pushing it up by only simultaneously lifting and pushing out the tongue 20—a movement 55 which could not occur accidentally.

An important feature of this invention is the manner in which curtains are mounted in the new bracket provided thereby. As shown in Fig. 1, the illustrated embodiment of this invention 60 is particularly adapted to support a drape assembly comprising a valance 22, side drapes 26 and a glass curtain 23. Since there is usually no occasion to adjust the position of the valance, the rod 24 which carries valance 22 is supported in a fixed seat 15. The problem of positioning the glass curtain is of major importance and the seat 21 is capable of permitting such adjustment over an unusually wide range by two separate means which cooperate to hang the glass curtain 75 23 with its lower edge at any desired dis-

tance from the floor without change in the color scheme or pattern of the lower portion of that curtain where predetermined design is highly important.

5 The rod 24 on which glass curtain 23 is hung by passing the rod through an open ended hem in the conventional manner is flat in cross section as clearly shown in Fig. 2. For the purpose of making adjustments of considerable extent the rod 24 may be rotated about its axis to roll the upper end of the curtain about rod 24. The curtain is then maintained in rolled position by reason of the configuration of seat 21. It will be readily understood how the seat 21, because it is formed as a flattened curve of 180°, inhibits the tendency of rod 24 to rotate and unroll curtain 23 when the parts are in the operative position illustrated by Fig. 2, all as more fully described and claimed in the copending application Serial No. 186,039, filed January 21, 1938.

20 After reaching an approximate adjustment of curtain length by rolling about rod 24, the bottom of the curtain is easily brought accurately to the desired position by inserting tongue 20 in an appropriate aperture 18. The tongue 20, as pointed out above is almost impossible to displace by accident; although readily inserted and withdrawn by hand when desired.

25 The side drapes 26 are hung on another rod 24 supported in a second support 11 exactly like 30 that already described, but hung on the front instead of on the back of the bracket 10. With this arrangement the glass curtains hang close to the window and freely inside of the side drapes and each is freely adjustable vertically to bring 35 their lower edges into line or at different heights as may be desired.

An important feature of the device, as shown, 40 is that it permits a wide latitude of curtain adjustment with a device of relatively small dimensions as compared with other brackets intended to achieve the same purpose.

45 For the purposes of our invention the dimension of seat 15 may be varied over a relatively wide range depending on the size of the curtain rod and the material employed in fabrication of the curtain. As a general rule the width of the hook-shaped seat should not be much greater than the width of the curtain rod. If the folds of the curtain are to be engaged in the hook, 50 it is wider than the rod, whereas, it should fit the rod if the bracket is placed beyond the edge of the supported fabric or preferably, as shown, engages the rod in a part which is exposed behind the fabric (e. g., as described below). Preferably, the depth of the seat is somewhat greater than the width of the rod to give efficient service.

55 It will be readily understood, however, that the dimension of the seat may be such as to adapt the same for use with a large variety of rods and curtain fabrics. Thus, it may be determined in advance what range of curtain rod widths will likely be used in combination with the brackets; and the brackets are then adapted to the entire range by suitable proportioning of seat 21. The width should then be not greatly in excess of the width of the narrowest rod contemplated and the depth will be preferably not substantially less than the greatest width of curtain rod which will likely be placed in the hook-shaped seat.

60 Although our drapery support as described herein may be made very attractive, it will ordinarily be completely hidden by a valance and rod of usual length extending beyond the member 10. For that purpose the stitched opening for the 70 75 75

valance rod may be interrupted at the point corresponding to the position of seat 15, and the upstanding lip of that seat will then extend into or through the hem of the valance. Or the hem 5 may be slit vertically so that the rod comes outside the hem for a short distance where it engages the seat 21. In Fig. 1 we have shown the valance broken away at the side of the member 10 for the purpose of better showing the detail 10 of the support member; but, as stated, it may extend any desired distance beyond the bracket and completely screen the same from the view of persons in the room.

When the support member is to be exposed we 15 may make it of a material that will harmonize with the interior metal or alloy, or of any other material of construction possessing sufficient mechanical strength for the purpose. It may be varnished, painted or enameled in solid colors or 20 suitable designs. Other obvious methods of decoration include covering with cloth, paper and the like or electro-plating.

Numerous variations in form obviously can be 25 made by skilled workmen, and these are also contemplated within the scope of this invention. Thus the seat 15 may be omitted or additional similar seats may be provided on any suitable extension means. Thus, a single bracket capable of 30 supporting separate rods to carry a valance, drapes and a glass curtain may be formed in accordance with the teachings of this invention.

The drawing and descriptive matter in connection therewith are to be taken as relating to the preferred form of our invention. Thus, we have 35 found that a bracket of the type shown and described is of particularly great value due to its general adaptability to a large variety of drapery combinations and its extreme flexibility in use. We do not, therefore, intend that the invention 40 shall be limited except by the scope of the following claims:

We claim:

1. An adjustable support for curtain rods and the like which comprises a cantilever bracket having a hook at the upper end thereof, means 45 at the opposite side thereof for attaching to a wall and an upwardly extending part affording support to said hook and being slotted at closely spaced intervals with similar slots having rounded upper and lower edges, and a double hook support member having at its lower end a hook adapted to receive a curtain rod and at its upper 50 end a hooked tongue with its inside shaped to fit closely the lower edge of any of said slots and of inside depth approximately equal to the space between the top of the hook and the upper edge of the slot, whereby the hook will hold on said lower edge when moved vertically substantially until it strikes the upper edge.

2. An adjustable support for curtain rods and the like as defined in claim 1, in which the upwardly extending part is spaced from the wall a distance greater than the width of the lower hook of the support member and is of length greater than said support member, and one such support member is engaged in a slot on the back of the upwardly extending part and another support member is engaged in another slot on the front of said upwardly extending part. 5

3. An adjustable support comprising an upwardly extending part slotted at intervals with similar slots having rounded upper and lower edges, and a double hook support member having at its lower end a hook adapted to receive a curtain rod and at its upper end a hooked tongue with its inside shaped to fit closely the lower edge of any of said slots and of inside depth approximately equal to the space between the top of the hook and the upper edge of the slot, whereby the hook will hold on said lower edge when moved vertically substantially until it strikes the upper edge. 10

4. A bracket type support for drapery and curtain rods comprising a substantially vertical strip portion having a plurality of spaced, substantially horizontal apertures therein, means to attach said strip portion in spaced relation to a wall surface and a rod supporting member bearing a hook adapted to be inserted in one of said apertures, 15 the outside depth of said hook being approximately equal to the width of one of said apertures. 20

5. A bracket type support for drapery and curtain rods comprising a substantially vertical strip portion having a plurality of spaced, substantially horizontal apertures therein, means to attach said strip portion in spaced relation to a wall surface and a plurality of rod supporting members each bearing a hook adapted to be inserted in one of 25 said apertures, the outside depth of said hook being approximately equal to the width of one of said apertures. 30

6. A bracket type support for drapery and curtain rods comprising a substantially vertical strip portion having a plurality of spaced, substantially horizontal apertures therein, means to attach said strip portion in spaced relation to a wall surface and a plurality of rod supporting members each having a hook adapted to be inserted in one of 35 said apertures, whereby a plurality of rods may 40 be supported at one end on a single bracket by inserting the hooks of a plurality of rod supporting members into said apertures with the rod supporting members depending from said apertures on both sides of said strip portion. 45
